UNITED STATES PATENT OFFICE.

HENRY MUNSEN, OF FORSYTH, MONTANA.

WATER-BICYCLE.

1,034,278.

Specification of Letters Patent. Patented July 30, 1912.

Application filed March 2, 1912. Serial No. 681,094.

To all whom it may concern:

Be it known that I, HENRY MUNSEN, a citizen of the United States, residing at Forsyth, in the county of Rosebud and State of Montana, have invented new and useful Improvements in Water-Bicycles, of which the following is a specification.

This invention relates to bicycles and the object of the invention is to provide a device 10 of this character which can travel on both land and water, and with these and other objects in view which will appear as the description progresses, the invention resides in the novel construction and arrangement 15 of parts hereinafter fully described and claimed.

In the accompanying drawings, Figure 1 is a side elevation of a device constructed in accordance with the present invention, the 20 float members being also shown in dotted lines in the position they are adapted to occupy when the device is employed upon land. Fig. 2 is a front view of the device. Fig. 3 is a rear view of the same. Fig. 4 is 25 an enlarged sectional view taken through the line 4—4 of Fig. 1. Fig. 5 is an enlarged sectional view upon the line 5—5 of Fig. 3.

In the drawings the numeral 1 designates the bicycle. This bicycle 1 is constructed in 30 the ordinary manner comprising the front or steering wheel 2, the rear or propelling wheel 3 and the usual frame 4 connecting the said wheels. The frame 4 is, of course, provided with a seat 5 and handle guiding 35 bars 6 which are connected with the steering post are supported upon the front forks of the frame.

The numerals 7 designate the front floats of the device. These floats preferably 40 comprise metallic drums each being closed upon all of their sides, and each preferably circular in cross section. The metal from which the floats are formed is bent and has its lower edges depending to provide what 45 may be termed the rudders 8. The floats 7 adjacent their front and rear portions are formed with annular depressions, the same being adapted for the reception of suitable bands 9. These bands have their central 50 inner portions formed with lugs or projections 10, the latter being adapted for the reception of the cross bars 11. The bars 11 are secured to the lugs 10 in any desired or preferred manner and the bars 11 each preferably 55 comprise two members, the same being centrally connected with a horizontal

head 12 of a T-shaped central board 13. This central board 13 extends the entire longitudinal length of the floats 7, and arranged between the bands 9 are collars 14 and 15. Each of these collars is formed with a pair of spaced lips and between each of the pairs of lips is pivotally connected one of the inclined arms of the float supports 16. These supports 16 at their apex or point of juncture are formed with suitable openings, the latter being adapted for the reception of bolts 17 which engage suitable openings provided within the front axles. The floats are arranged at a suitable distance away from each side of the bicycle frame, as clearly illustrated in the drawings, and in order to sustain the same when the device is employed upon water as well as to lock the said floats to the positions indicated by the dotted lines in Fig. 1 of the drawings when the device is employed on land, I have employed suitable guy ropes or cables 19 and 20, when positioned adjacent the front of each of the floats and the other 70 arranged adjacent the rear of the said floats and all the guys being connected through the medium of suitable loops to the handle bar 6. The rear guys 20 comprise a pair of elements one being formed with a ring 21, 75 the second element being provided with a hook adapted to engage the ring. Both of the guys 19 and 20 have their lower extremities formed with helical springs 22 at their 80 points of connection with the floats. 90

The points of juncture of the walls of each of the floats 7 are, as previously set forth, offset to provide what may be termed the rudders 8 and interposed between the said offset is a piece of suitable flexible material 95 23. The offsets are connected to the said member 23 through the medium of a plurality of rivets 24 and the front portion of each of the floats is formed with a nose 25 and arranged below the top of the float is an 100 opening to which the helical spring of the guy member 19 is attached. The rear spring, that connected with the guy 20, is secured within a suitable eye 26, and arranged upon the upper face of the float, 105 preferably adjacent the said eye 26, is a valve 27. This valve is normally self-closing and the same is adapted to be engaged by an ordinary air pump, such as those commonly employed for inflating bicycle tubes 110 and whereby air may be admitted to the hermetically sealed floats when desired.

The numerals 28 and 29 designate the rear floats of the device. These floats are constructed in a similar manner described in connection with the floats 8 and each of 5 the said floats is provided with the offset supporting members 30 which are secured to the axle of the bicycle frame. The floats are also provided with the spring guys 31 and 32 which, in this instance, have their loops engaging the seat post of the frame. 10 The rear floats are each formed with a suitable band 33, the upper portion of which is provided with spaced ears 34, and adapted to be positioned between the said spaced 15 ears are the bearings 35 adapted for the reception of the transversely arranged axle 36. The lower extremities of the bearings are twisted so as to allow the said bearings to be arranged in a direct plane with the 20 axle 36. This axle 36 preferably comprises three distinct members designated respectively by the numerals 37, 38 and 39. The 25 end members 37 and 39 rest within the bearings 35 and have their free ends riveted to what I term couplings 40. These couplings 40 are provided with a plurality of centrally arranged offset cup members 41, the latter adapted to receive the radially arranged spokes 42 of the driving wheels. 30 The extremities of the spokes 42 are each provided with paddles 43 and these paddles may be provided with peripheral reinforcements consisting of a pair of spaced wires or the like, if desired. The radial spokes 42 35 may be also reinforced in any desired manner, so that rigid wheels sufficient to overcome the resistance of the water may be provided. The central member 38 of the axle 36, is provided with a longitudinally 40 adjustable wheel 44. This wheel 44 has its central portion formed with a collar 45, and the said collar is provided with an opening adapted for the reception of a retaining screw 46, whereby the wheel is held in its 45 adjusted position.

The transversely arranged spacing members 47, which correspond with the members 11, are centrally provided with a T-shaped central board 48, and the rear one of these 50 spacing members is formed with a pair of frames designated respectively by the numerals 49 and 50. Each of these frames is preferably constructed of wire having its lower portion, or that adapted to be positioned within the water and secured to the spacing member 47, reinforced and bent at an angle toward the upper portion of the device. The wire frames each comprise a pair of members, the lower portions of 55 60 which being arranged in a spaced parallel plane with each other and are rounded to correspond with the peripheral contour of the paddles.

The frames are covered with some suitable material such as duck cloth or rubber 65

or the like, to provide water guards 51, so that the operator of the device seated upon the bicycle will not be splashed when the device is in operation upon the water.

The numeral 52 designates the driving belt of the device. This belt 52 is constructed of some suitable flexible material and is of a width sufficient to tightly engage the faces and sides of the rear bicycle wheel 3 and the wheel 44 secured to the axle 36. In order to sustain the belt tightly upon the said wheels I have provided the meeting ends of the belt with adjusting members 53 and 54. These members preferably comprise a pair of threaded elements having their central portions engaged by an oppositely threaded nut or turnbuckle and the belt is centrally formed with a plurality of spaced openings 55, whereby water is free to drop therefrom during the operation of 85 the device.

From the above description taken in connection with the accompanying drawings, it will be noted that I have provided an extremely simple, comparatively cheap and light appliance for any ordinary bicycle whereby the said wheel may be free to travel over land or water as desired, and while I have illustrated and described the preferred embodiment of the invention as 95 it now appears to me, minor changes in the details of construction, within the scope of the following claims may be made if desired.

Having thus fully described the invention, what I claim as new, is:—

1. In a device for the purpose set forth, the combination with a bicycle having the ordinary running gear, a pair of floats, means for sustaining each pair of floats in 105 spaced relation with each other, a center board secured to said sustaining means, a pivotal connection between each pair of floats with each of the bicycle axles, resilient guy members for sustaining the floats below 110 the plane of the bicycle wheels and for sustaining the said floats above the plane of the bicycle wheels.

2. The combination with a bicycle of a pair of metallic air tight floats, each of said floats having their lower extremities formed with a depending center board, spaced bands around the floats, ears upon the bands, substantially V-shaped members connected with the ears, a pivotal connection between the 120 said V-shaped members and the axles of the bicycle, and resilient guy members connecting the opposite ends of the float with the frame of the bicycle.

3. The combination with a bicycle, of a 125 pair of metallic air tight floats arranged adjacent each of the sides of the bicycle, V-shaped supports connected with the axles of the bicycle and adapted to normally retain the floats below the plane of the wheels of 130

the bicycle, resilient guys connecting the ends of the floats with the frame of the bicycle, spacing members for each of the opposite floats, a center board connected with 5 the said spacing members, a shaft connected with the rear pair of floats, a longitudinally movable wheel upon the shaft, paddle wheels upon the shaft, and a belt connection between the rear wheel of the bicycle and 10 the wheel of the shaft.

4. The combination with a bicycle, of a pair of floats arranged adjacent and normally below the front and rear wheels of the bicycle, a pivoted support connecting the 15 bicycle with each of the floats, guy members connecting the ends of the floats with the frame of the bicycle, bearing members upon

the rear pair of floats, a shaft mounted within the bearings, hubs upon the shaft, spokes upon the hubs, paddles connected 20 with the floats, a wheel upon the shaft, a perforated belt connecting the said wheel with the rear wheel of the bicycle, means for adjusting the belt, a spacing bar for the floats, a rudder upon the spacing bar, a pair 25 of spaced frames upon the spacing bar, and paddle guards connected with the frames.

In testimony whereof I affix my signature in presence of two witnesses.

HENRY MUNSEN.
